UNITED STATES PATENT OFFICE.

FRANK I. HITCHCOCK, OF BRIDGEPORT, CONNECTICUT.

VAPORIZER FOR HYDROCARBON-ENGINES.

No. 799,791.

Specification of Letters Patent.

Patented Sept. 19, 1905.

Application filed August 21, 1903. Serial No. 170,256.

To all whom it may concern:

Be it known that I, FRANK I. HITCHCOCK, a citizen of the United States, and a resident of Bridgeport, in the county of Fairfield and State of Connecticut, have invented a certain new and useful Vaporizer for Hydrocarbon-Engines, of which the following is a specification.

My invention relates to vaporizers for gas-
engines, its object being to construct a vapo-
rizer that will be automatic in its operation,
whereby the air and fluid supply are properly
mixed for all speeds of the engine.

Heretofore when vaporizers have been sup-
plied with an air-valve which when lifting to
admit the air to the vaporizing-chamber also
actuated the fluid-supply valve, or, in other
words, when the air-inlet controlled the fluid
or gasolene supply it was impossible to obtain
a perfect mixture of air and fluid for all speeds,
as one or the other would be deficient. If
the air-valve was set for a low speed, it would
not lift sufficient to actuate the fluid-valve to
admit the required amount of fluid to form
the proper mixture, and at a high speed there
would be a scarcity of air. On the other hand,
if the air-valve was set for high speed there
would be too much air for a low speed. There-
fore in order to maintain the proper mix-
ture at all speeds an auxiliary air-cock lo-
cated in the suction-supply pipe was an ab-
solute necessity. I overcome these difficulties
by means of a weighted air-valve which is
primarily set to admit the air necessary for
the highest speed required, combined with an
independently-operating piston or plunger to
operate the fluid-supply valve. This plunger
is made light, so as to be actuated first, so
that under a slow speed, where the suction
caused by the engine-piston is light, and con-
sequently less fluid is drawn down into the
vaporizing-chamber, the plunger will actuate
the fluid-supply valve sufficient to furnish
the required amount of fluid to run the engine
at the slowest speed, while the air-valve is
weighted proportional to the suction of the
piston, so that when running slow the re-
quired amount of air will be admitted to make
the proper mixture at such slow speed. In
other words, the plunger is lifted the same
distance for all speeds, and the amount of
fluid drawn down is regulated entirely by the
speed of the engine, as the greater the speed
the stronger will be the suction, and there-
fore the discharge of fluid will be greater at
a high speed than at a low speed. On the

other hand, the weighted air-valve is regu-
lated entirely by the suction induced by the
speed of the engine, so that the amount of
air and fluid is automatically admitted to the
vaporizing-chamber in proper portions for all
speeds and under all circumstances.

Another feature of my improved vaporizer-
valve consists in swiveling the inlet and out-
let elbows so that they can be readily set at
any angle with respect to the proper engine
connections without disturbing the position
of the vaporizer.

To enable others to understand my inven-
tion, reference is had to the accompanying
drawings, in which—

Figure 1 represents a broken side elevation,
partly in section, of the vaporizer. Fig. 2 is
an upper plan view of the vaporizer-body with
the cap or bonnet removed. Fig. 3 is a de-
tail view of the bonnet carrying the fluid-valve
and adjustable stops for limiting the upward
travel of the air-valve and the plunger for ac-
tuating the fluid-valve looking in the direc-
tion of arrow *a* of Fig. 1. 80

The construction and operation are as fol-
lows: 1 is the body of the vaporizer; 16, the
bonnet. 3 is the air-inlet elbow, having the
taper face 3^a, adapted to make a tight connec-
tion with the taper seat 4 in the body 1. 5 is 85
a retaining-bolt whose threaded end engages
a threaded hole in the web 6 of the body 1, as
shown at Fig. 1. 7 is the outlet-elbow, hav-
ing the taper face 7^a to engage with the taper
seat 8 of the body 1, and 9 is its retaining-screw. 90
By this arrangement these elbows can be
swiveled on their respective seats so as to
make the proper connections with the air-in-
let pipe and the pipe carrying the mixture to
the explosive chamber of the engine without 95
disturbing the position of the vaporizer. By
this construction the vaporizer can be more
readily attached and detached without disturb-
ing the pipe connections.

10 is the air-valve, having the weighted head 100
10^a. As shown, this head is integral with the
valve; but it can form a separate part of the
same, if desired.

10^b is the valve or guide stem, which has a
free vertical movement in the hole 11^a, Fig. 105
2, extending through the web 6 in the bottom
of the vaporizer-body.

11 is the air-port extending through the par-
tition 12, whose area is of course equal to the
area in cross-section of the elbow 3. 110

13 is the piston or plunger operating be-
tween the vaporizing-chamber 17 and the air-

chamber 17^a, and it actuates the fluid-supply valve in the manner presently to be described. This piston operates freely in the hole 13^a, Fig. 2, provided in the partition 12, and it 5 has the head 13^b, adapted to rest on the top of said partition to limit its extreme downward movement. The piston is cupped out on its under side to make it light enough to respond to the slightest suction of the engine-piston.

10 14 is the guide-stem for the plunger and, like the guide-stem of the air-valve, operates freely in a hole 14^a, Fig. 2, provided in the web 6, and it also projects without the vaporizer and is made tubular to insure lightness.

15 15 is an adjusting-screw mounted in a threaded hole of the bonnet 16. The lower end of this screw projects within the vaporizing-chamber 17 and directly over the air-valve to limit the upward movement of said valve.

20 18 is a boss integral with the bonnet 16, extending above and below the same to carry the fluid-supply valve 19 and the adjusting-screw 20 to limit the upward movement of the plunger 13. The fluid-valve is of the usual 25 construction, having the overlying tension-spring 21 and the adjusting-screw 22.

23 is a threaded hole to receive the fluid-supply pipe, (not shown,) and 24 is a small hole in the back wall of the hole 23 for conveying the fluid to the valve 19.

30 The operation of the devices is as follows: The adjusting-screw 15 is set to limit the upward movement of the air-valve 10 to admit the necessary amount of air required for the 35 engine when running at full speed. The adjusting-screw 20 is set to limit the upward movement of the plunger 13. When, therefore, the plunger strikes against this stop-screw, it will have lifted the fluid-supply 40 valve sufficient to admit the necessary amount of fluid required for the lowest speed of the engine. The travel of this plunger is constant, always striking against its stop-screw and lifting the fluid-supply valve 19 the 45 same distance under all speeds of the engine. Therefore the extra quantity of fluid required to run above the lowest limit of speed will be drawn down into the vaporizing-chamber through the medium of the suction caused 50 by the movement of the piston of the engine, which suction will of course vary with the speed. It will be understood that there is also a slight suction when the engine is running at its lowest speed. Therefore the 55 amount of fluid that would naturally be discharged from the fluid-supply valve by gravity and the amount drawn out by suction at its lowest speed will determine the position of the stop-screw 20.

60 As the stem 14 is amply sufficient to guide the plunger, the skirt portion of said plunger could, if desired, be dispensed with. This will leave the head portion 13 normally resting over the port in which said skirt now operates.

65 The weight of the air-valve is proportioned

to the requirement of air necessary to maintain the proper mixture when running at all speeds, so that when running at the slowest speed the suction at this point will just lift the valve from its seat. At the highest 70 speed, as before mentioned, the valve will be carried up by the increased suction against the adjustable stop 15 to give a full-open port. In all intermediate speeds between the highest and the lowest the weighted valve will automatically maintain a height or opening proportional to the requirements of the engine. The weight of the air-valve is proportioned to the diameter of the engine-cylinder. Therefore the larger the diameter of the cylinder 80 the greater will be the suction, and consequently the valve must be correspondingly weighted.

As the piston-plunger must necessarily have a free vertical movement, it naturally follows 85 that some air will pass into the vaporizing-chamber when the piston is lifted to actuate the fluid-supply valve.

From the foregoing description it will readily be seen that my improved vaporizer 90 is self-regulating under all speeds and requires no auxiliary air-cock in the suction-supply pipe.

Having thus described my invention, what I claim as new, and desire to secure by Letters 95 Patent, is—

1. The combination in a vaporizer having a body portion, a vaporizing-chamber, an air-inlet port and a fluid-supply valve, of a weighted valve for said port, an adjustable stop set 100 to limit the upward movement of the valve to represent a full-open port at high speed, a piston-plunger operating between the air-chamber and the vaporizing-chamber to actuate the fluid-supply valve, an adjustable stop 105 to limit the upward movement of the plunger, for the purpose set forth.

2. A vaporizer, comprising a body portion having a fluid-supply valve, a vaporizing-chamber and an air-chamber separated by a 110 partition having an air-port therein, a valve therefor, an adjustable stop set to limit the upward movement of the valve to represent a full-open port, said valve carrying a weight to regulate the lift of said valve proportionally to the speed of the engine to which said vaporizer is adapted to be attached, said partition having an opening adjacent to said air-port, a piston-plunger operating in said opening between the air-chamber and the vaporizing-chamber to actuate the fluid-supply valve, 115 an adjustable stop to limit the upward movement of said plunger, all combined and arranged so that the air and fluid supply are automatically proportioned to the varying 120 speeds of the engine, for the purpose set forth.

3. A vaporizer, comprising a body portion having an air-chamber and a vaporizing-chamber separated by a partition, said partition having an air-port therein, a valve there- 125

for, said valve having a stem, a web central with said air-chamber in which said stem is guided, a cap or bonnet for said body portion carrying an adjustable stop set to limit the upward movement of said valve to represent a full-open port, said valve carrying a weight to regulate its lift for different speeds, said partition having an opening adjacent to said air-port, a piston-plunger therefor, which plunger operates between said air-chamber and vaporizing-chamber, said bonnet carrying a fluid-supply valve to be actuated by said

plunger, an adjustable stop in said bonnet to limit the upward movement of the plunger, said plunger having a stem adapted to be guided in said central web, for the purpose set forth.

Signed at Bridgeport, in the county of Fairfield and State of Connecticut, this 6th day of July, A. D. 1903.

FRANK I. HITCHCOCK.
